United States Patent Office

Des. 217,653
Patented May 19, 1970

217,653

SIGN OR SIMILAR ARTICLE

Clark L. Lofgren, Brooklyn Center, Minn., assignor to
The Cornelius Company, Anoka, Minn., a corporation of Minnesota

Filed Jan. 16, 1969, Ser. No. 15,378

Term of patent 14 years

Int. Cl. D20—03

U.S. Cl. D96—12

FIG. 1 is a front elevational view of a sign showing my new design, the rear being plain and unornamented as indicated in FIGS. 2 and 3;

FIG. 2 is a top plan thereof; and

FIG. 3 is an elevational view taken from one side thereof, the opposite side being a mirror image of the side shown.

I claim:

The ornamental design for a sign or similar article, substantially as shown and described.
